BUTTON STITCHING MACHINE

Carl W. Johnson, Brooklyn, N.Y., assignor to American Machine & Foundry Company, a corporation of New Jersey

Filed July 18, 1963, Ser. No. 296,039

11 Claims. (Cl. 112—110)

This invention relates to stitching machines, and more particularly to improvements in stitching machines which sew or stitch buttons and like fastening devices to garments, such as men's and women's coats and the like.

The invention constitutes improvements to button stitching machines of the type disclosed in Patterson et al, Patent 2,739,550, copending Johnson et al. application, Serial No. 20,142, filed April 5, 1960 now Patent 3,132,613, granted May 12, 1964, Johnson et al. application, Serial No. 20,693 now Patent 3,121,411, granted February 18, 1964, and copending Pedersen application, Serial No. 54,215, filed September 6, 1960 now Patent 3,125,046, granted March 17, 1964 for Work Support Table for Button Stitching Machine.

In stitching buttons to garments, such as men's and women's coats, it is desirable that the demands of particular fashion requirements be met. That is, a present demand may require the use of two-hole buttons. Then again, the style may require that a four-hole button be used, and that parallel stitching or perhaps a cross stitch pattern be followed. One of the features of the invention is the provision of novel mechanism which makes it possible to meet all of the requirements for effecting the stitching of two-hole buttons as well as four-hole buttons. The invention also provides mechanism which makes it possible to adapt the stitching machine in which it is embodied with great rapidity so as to handle runs or lots of buttons of varying sizes and hole spacings. Thus, for a given run it may be desired to stitch two-hole, twenty-four (24) ligne buttons, and for another run either two-hole or four-hole thirty (30) ligne buttons. Also runs can be made with four-hole buttons with either parallel or cross stitch formations. These novel results are obtained by means which control the motion of the work supporting table in such manner that the "throw" thereof is made to conform to the requirements of a two-hole or a four-hole button, its size and hole spacing, and, in the case of a four-hole button, the selected stitching pattern.

The invention also resides in the provision of means which make it possible to compensate for variations in thickness of the goods or material to which a button is being stitched. Because of this novel feature the winding loops and the locking stitch or stitches passing therethrough now can be located properly between the underside of a button and the surface of the work to which a button is being attached.

In a normal weight man's suit coat, for example, the locking stitch or stitches securing the winding loops of thread from unwinding is or are approximately at the midpoint of the loops of thread attaching a button to the work. In the case of the attachment of a button to the heavy goods of an overcoat, the locking threads would not be properly located as in the case of the suit coat above mentioned. The invention solves this problem by providing novel work support table control mechanism which selectively controls its motion so that the locking stitches always will be properly disposed between a button and the work to which it is attached.

It is an object of the invention to provide novel means for effecting the attachment of buttons of different types and sizes to selected work in a manner closely approximating hand stitching.

It is a further object of the invention to provide novel stitching mechanism which makes it possible to stitch two

2

and four-hole buttons to selected work and use buttons varying in size and hole spacing.

It is a further object of the invention to provide a novel button stitching machine wherein means are provided for controlling the movement of the work supporting table in such manner that buttons having different numbers of holes and spacing can be stitched, and different selected stitching patterns can be followed in attaching four-hole buttons to the work.

The invention also consists of the provision in a button stitching machine having a novel work supporting table which can be so controlled in its movements relative to the needle that winding and locking stitches relative to loops of thread connecting a button to the work are disposed in a predetermined relationship preferably centrally between the underside of a button and the top surface of the work to which it is attached regardless of variations in the thickness of the work material.

The invention further consists in novel selectively operated mechanism which controls the movement of the work support table of a button stitching machine such that runs or lots of buttons having two or four holes and differently spaced holes can be handled in a machine embodying the invention and wherein, regardless of the thickness of the goods to which a button is being attached, compensating adjustments can be made to insure the proper disposition of the winding and locking stitches in the shank or post securing the button to the goods.

With these and other objects not specifically mentioned in view, the invention consists in certain combinations and constructions which will be fully described hereinafter, and then specifically set forth in the claims hereunto appended.

In the accompanying drawings which form a part of this specification, and in which like characters of reference indicate the same or like parts:

FIGURE 1 is a plan view, partly in section, of a work support table and its actuating mechanism of a button stitching machine showing a preferred embodiment of the invention,

FIGURE 2 is a partial end elevation, taken on line 2—2 of FIGURE 1, illustrating the post winding lock stitch control cam,

FIGURE 3 is a plan view of the post winding lock stitch control mechanism,

FIGURE 4 is a side elevation, partly in section, of the mechanism shown in FIGURE 1,

FIGURE 5 is a sectional front elevation, taken on line 5—5 of FIGURE 4, illustrating the work support table actuating cams,

FIGURE 6 is a partial plan view of the work support table reciprocating arm illustrating its adjusting feature in detail,

FIGURE 7 is a sectional end elevation taken on line 7—7 of FIGURE 6, and

FIGURE 8 is a front elevation of the reciprocating arm adjusting mechanism.

A machine in which the invention finds ready application and use is one such as shown in Patterson et al. Patent 2,739,550, or Pedersen Patent 3,125,046. These machines are provided with mechanism for projecting a needle N having an eye located between its ends back and forth through the holes of a button to be sewed and the work, so that the thread which passes through the eye of the needle is disposed in continuous loops in the button and the work and about these loops and locked against unwinding in a manner closely simulating "hand" stitching.

In the drawings which illustrate a preferred embodiment of the invention installed and operating in the type of machine described above, there is provided a work supporting table, designated T, essentially the same in

construction and operation as that shown in Pedersen, Patent 3,125,046. This table is formed of coacting members and units which enable it to travel longitudinally and laterally and thereby dispose work W and a button carried in a chuck (not shown) mounted on Table T properly relative to needle N for effecting the attachment of the button to work W. Driving mechanism D also similar in construction and operation to that shown in Pedersen patent is responsible for the proper timed reciprocation of needle bars B, the operation of the several cams and linkages which effect the longitudinal and lateral motion of table T, and all other coacting parts and units of the machine necessary to attach a selected button or selected buttons to work W. It will be noted that, as shown in FIGURES 1 and 4, table T is provided with a work support member M and a clamping plate P which secures it on member M for stitching operations. This construction is similar to that disclosed in the Pedersen application.

As used herein "longitudinal" movement of table T, means that to and from needle N. "Lateral" movement is motion at right angles to the longitudinal path of travel of table T. In certain stitching patterns, table T is moved through a combination of paths of travel which can be defined as "diagonal."

In accordance with the invention, work support table T is so constructed and operated as to make possible a rapid change over to selectively change not only its path or paths of motion but also to selectively change the extent of its movement. In this way runs or lots of selected buttons, such as two-hole or four-hole buttons, of varying sizes, can be stitched to the work or material W, and at the same time the spacing between the button holes can be properly and accurately accommodated.

Referring to FIGURES 1, 6, 7 and 8, longitudinal motion is imparted to table T by means of a lever 30 having one arm connected to a pin 27 depending from the underside of table T which is suitably supported by mechanism (not shown) similar to that shown and described in the above referred to Pedersen patent. In order to effect a desired or selected rapid change over to convert the machine to handle a selected type of button, the other end of lever 30 is provided with an extension 10. A plate 14 attached by screws 12 to this extension is provided with an arcuate slot 16 corresponding with a similar slot 18 formed in extension 10. At its front or right hand side, as viewed in FIGURES 6 and 7, plate 14 is provided with grooves 20 in which are movably clamped a plurality of suitably spaced indicator lugs or tabs 22. Each tab 22 is provided with a narrow slot 24 which serves as an indicator or registration mark. A registration plate 26 slidably supported on the upper face of plate 14 carries a pair of spaced downwardly projecting lugs 28. These lugs slidably engage in slot 16 in plate 14 and control the path of travel of plate 26 on plate 14. Formed centrally in plate 26 is a hole through which extends the shank of a T-head bolt 29, the top portion of which supports a swivel joint head of a connecting rod bolt 32 secured to lug 34 which forms one end of connecting rod member 36.

The opposite end of connecting rod member 36 is provided with a pair of longitudinally spaced lugs 38 having a suitable horizontal bore in which the rear end of connecting rod 40 is slidably supported. The front end of connecting rod 40 is adjustably secured by bolt 42 (FIGURES 4 and 5) in a slot 44 formed in the free end of cam lever 46. This lever is pivotally mounted on horizontal shaft 48 held by a suitable bearing lug 50 forming an integral part of and projecting from worm gear driving housing 52.

As shown in FIGURES 1, 4 and 5, cam lever 46 supports a stud 54, one end of which carries a cam follower 58. The other end of stud 54 is secured in a selected adjusted position in lever 46 by set screw 56. This arrangement makes it possible to adjust the operative posi-

tion of cam follower 58 relative to a selected cam 60 or 62, merely by loosening set screw 56, shifting stud 54 laterally in lever 46 to position cam follower 58 for coaction with selected cam 60 or 62 and then again tightening set screw 56 against stud 54 to secure it and cam follower 58 carried thereon against movement in lever 46 (see FIGURE 5). Cam follower 58 is maintained in tracking engagement with a selected cam 60 or 62 by spring 49. One end of spring 49 is attached to the frame F of the machine, its other end is secured to the free end of lever 46.

Connecting rod 40 comprises a head 41 formed on one end resting against the face of one lug 38. Its other end is threaded and mounted in a coupling member 43 pivotally connected to lever 46, as described above. A lock nut 45 maintains rod 40 in a preset coupled arrangement with member 43. Spring 47 encircling rod 40 between the second lug 38 and lock nut 45 provides a resilient yieldable sliding coupling between rod 40 and member 36. In this way in case of a jam no breakage of parts can occur. Also, this construction allows table T to be stopped at a predetermined adjusted position during the formation of a locking stitch, as described hereinbelow.

Cams 60 and 62 are designed and used to impart longitudinal reciprocating motion to work support table T by means of the linkage described hereinabove. Due to the fact that the spacing between the holes of a standard two-hole button is different from that of a standard four-hole button of the same size, the position of cam follower 58 is adjusted such that it engages with cam 60 when a two-hole button is being stitched to the work, and with cam 62 when a four-hole button is being sewn.

Since the spacing between the two holes of a two-hole button, as well as that between the holes of a four-hole button may vary with the size of the button, novel means are provided for insuring that the work and button which is to be attached are so disposed relative to needle N that stitching operations can be effected without jamming, or breakage of joints or the needle. This important result is obtained by the structure described hereinabove where-in the stroke imparted by a selected cam 60 or 62 to actuating arm 30 is adjusted and set to conform with the hole spacing of a selected two or four-hole button. This is done by loosening T-head bolt 29 and sliding connecting rod bolt in one direction or the other in arcuate slot 16 until the effective operating length of the connecting rod linkage comprising connecting rod member 36 and connecting rod 40 pivotally attached to lever 46 corresponds to that required to insure proper movement of table T for the projection of needle N back and forth through the holes of a selected button without obstruction. This movement of bolt 32 which also moves plate 26 continues until a selected calibration, such as "2" on plate 26, is aligned with a corresponding calibration 24 on a tab or lug 22 whereupon bolt 29 is tightened. The machine then is ready to stitch a run of selected buttons to the work as required. Arcuate slots 16 and 18 are provided to maintain operating symmetry between the holes of the button being stitched and table T regardless of the selected adjusted position of bolt 29 in these slots.

In the same manner as disclosed and described in the above referred to Pedersen patent, bell crank lever 72 is provided for effecting the lateral motion of table T. In accordance with the invention, however, one arm of lever 72 is formed with an extension 64 which is similar in construction to extension 10 of actuating arm 30. Extension 64 is provided with an arcuate slot 66 (FIGURE 1) and has secured thereto a plate 68 formed with an arcuate slot which matches with that in extension 64. This construction is the same as that shown in FIGURES 6, 7 and 8. As in the case of plate 14, plate 68 also carries a plurality of registration or indicator tabs or lugs 70. A registration plate 74 similar to plate 26 is slidably mounted on plate 68 and engages with a stud 76 extending upwardly through the arcuate slots

in extension 64 and plate 68 in a manner similar to stud 29, and can be moved in these slots in order to effect desired adjustments in the extent of lateral motion of table T. Slot 66 and its matching slot in plate 68 perform the same function as slots 16 and 18 described hereinabove.

The top end of stud 76 supports the swivel joint end 77 of a connecting rod 78 which is maintained in operative position thereon by nut 79. The other end of rod 78 is connected to the free end of cam lever 80 pivotally mounted on shaft 48 (FIGURES 4 and 5). Cam lever 80 is provided on its opposite faces with a hub 81 and a bore 83 therethrough. A stud 82 having a cam follower 84 mounted on one end is slidably mounted in bore 83, and is held by set screw 85 in a selected adjusted position relative to cams 86, 88 and 90 which are mounted side by side on cam shaft 92 on which cams 60 and 62 also are mounted. Cam follower 84 is maintained in tracking engagement with a selected cam 86, 88 or 90 by means of spring 87 having one end connected to the free end of lever 80, and its other end attached to the machine frame F.

Cams 86, 88 and 90 are designed and used through the linkage described above to impart the required lateral reciprocating motion to work table T. Each cam serves to provide a specific type movement in accordance with a selected stitching pattern determined by the particular two or four-hole button to be stitched.

Cam 86 is used when a two-hole button is to be stitched. Cam 88 is used when a four-hole button is to be attached with a cross stitch pattern. Cam 90 is used for a four-hole button, but only when a parallel stitching pattern is desired.

Since, as mentioned hereinabove, the distances between holes in different sizes and types of buttons vary, the machine can quickly be changed to accommodate the requirements as to lateral motion of table T for stitching a run or lot of buttons of a selected size by simply loosening the nut 79 on bolt 76, and sliding bolt 76 in one direction or the other in slot 66 until a selected marking or calibration on plate 74 is aligned with a complementary calibration on one of the tabs 70 secured to plate 68 which represents the extent of lateral movement table T should travel for proper stitching of the selected button.

It will be appreciated that there are two adjustments which are made in order to adapt the machine to stitch a selected button to the work. The first described is the adjustment for controlling the extent of longitudinal movement of table T. The second adjustment controls the extent of lateral movement of table T. The order in which these adjustments are made is not controlling. The conjoint operation of a selected cam 60 or 62 on the one hand with a selected cam 86, 88 or 90 on the other, together with the proper selected positioning of plates 26 and 74 makes it possible to effect the desired stitching pattern for two and four-hole buttons.

The several cams are provided with the required number of high and low portions to insure that through drive mechanism D, and coating operating mechanisms shown herein and also similar to that disclosed and described in Patterson et al. patent, Pedersen Patent 3,125,046, and Johnson et al. Patents 3,121,411 and 3,132,613, the necessary number of stitches, post windings and lock stitches will be made in effecting the desired stitching of each button to the work. Since the mechanism for stitching, winding and forming of locking stitches does not form a specific part of this invention further showing and detailed description is deemed unnecessary to an understanding of the invention and is omitted.

As shown in FIGURE 1, the other end of bell crank lever 72 is connected to a connecting rod 73, the other end of which is connected at 75 to table T. Thus, through this connection, the oscillation of bell crank lever 72, due to the rotation of cams 86, 88 or 90 engaging

cam follower 58, effects the desired lateral movement of table T. The combined operation of cam 60 or 62 and a selected cam 86, 88 or 90 effects the desired path of travel of table T relative to needle N in the course of stitching a selected button and the formation of winding and locking stitches and comprises a combination of horizontal longitudinal, lateral and diagonal movements to accomplish these results. As in the case of the mechanism disclosed in Pedersen Patent 3,125,046, cam shaft 48 makes one revolution only during the entire stitching cycle.

In the process of stitching a button to the work, such as a man's suit coat, it is desirable that the wrapping or winding stitches about the loops of thread attaching the button to the work, and the locking stitch or stitches be centered relative to the underside of the button and the upper surface of the work. Heretofore, if any variation in thickness in work occurred, as in the case of difference in thickness between a suiting material and a thicker or heavy overcoat material, these last named stitches would not be so disposed relative to the button and the work. This problem is solved by the present invention.

Referring to FIGURES 1, 2, 3 and 4, the machine is provided with a cam 94 mounted on cam shaft 92. Cam 94 is tracked by cam follower 96 mounted on cam lever 98 pivotally supported on shaft 48. The free end of cam lever 98 is connected pivotally to one end of a connecting rod 100, the other end of which is connected pivotally to one arm of a bell crank lever 102 rockably mounted on pin 104 supported in a lug 106 on machine frame F (FIGURE 4). During each cycle of the machine when a lock stitch is made in being passed through the wrapped "post" attaching a button to the work, in the manner similar to that disclosed in Patterson et al. Patent 2,739,550, the free end 107 of arm 105 of bell crank lever 102 is swung by cam 94 from broken line to full line position shown in FIGURE 3. In this position the end of arm 105 is disposed to be engaged by stop screw 110 adjustably mounted in a lug 112 on extension 10 of actuating arm 30. The engagement of end 107 with stop screw 110 arrests the forward movement of arm 30 and thereby the movement of table T. By suitable adjustment of stop screw 110 the centered position of a locking stitch which is made during the engagement of end 107 of arm 105 with stop screw 110, can be controlled quite accurately. Stop screw 110 can be provided with a calibrated head 114 so that the limit of forward movement of table T can be set with a fine degree of accuracy, and thereby insure that the lock stitch always will be placed centrally between the button and the work in accordance with the thickness of the work to which a button is to be attached.

What I claim is:

1. In a button stitching machine having means for projecting a threaded needle back and forth through selected button holes and the work to which a button is to be attached to form a plurality of loops of thread connecting said button thereto, comprising in combination a support table for said work, means for forming a plurality of winding loops and locking stitches around and through said loops of thread connecting said button to said work, means for moving said table in a longitudinal path of travel relative to said needle, means for moving said table in a lateral path of movement relative to said needle whereby to position selected holes of said button in the path of travel of said needle, operating mechanism for actuating said means for effecting the movement of said table in said longitudinal and lateral paths of travel, and means for controlling said mechanism to limit the extent of said movements of said table in accordance with the number of holes and spacing between the holes of a button being stitched.

2. In a button stitching machine having means for projecting a threaded needle back and forth through selected button holes and the work to which a button is to be attached, comprising in combination a support table for

said work, means for moving said table in a longitudinal path of travel relative to said needle, means for moving said table in a lateral path of movement relative to said needle whereby to position selected holes of said button in the path of travel of said needle, operating mechanism for actuating said means for effecting the movement of said table in said longitudinal and lateral paths of travel said mechanism comprising a cam shaft, means for driving said cam shaft in timed relationship with the operation of said means projecting said threaded needle back and forth through selected holes in said button and said work, and in forming winding loops and locking stitches around and through the loops of thread connecting said button to said work, a first group of cams on said cam shaft for effecting the movement of said table in said longitudinal path of travel, a second group of cams on said cam shaft, for effecting the controlled lateral movement of said table, a cam lever for each of said groups of cams each of said levers having an adjustably mounted cam follower for engaging a selected cam corresponding to the type of button to be stitched to said work, actuating levers attached to said table, a connecting rod attached to each one of said levers and to one of said cam levers, and means for adjusting the point of connection of each of said levers to its respective table actuating levers to limit the extent of longitudinal and lateral movement of said table in the attachment of two-hole buttons and four-hole buttons with parallel stitches, and to limit the extent of diagonal movement of said table during the conjoint operation of both of said table actuating levers during the attachment of a button to said work.

3. The invention defined in claim 2, wherein one end of each of said table actuating levers comprises an extension provided with an arcuate slot, a slidably adjustable member carried by each connecting rod engaging in its respective arcuate slot in its respective extension on its actuating lever, and means for securing each of said members in a selected position in its respective slot corresponding to the longitudinal and lateral extent of movement the table is to take in the attachment of a selected two or four-hole button.

4. The invention defined in claim 3 wherein each arcuately slotted extension carries a support plate having an arcuate slot matching that in said extension, and said slidably adjustable member also extends through said matching slot in said plate, a plurality of indicating tabs adjustably mounted on said support plate, and a graduated calibrated plate having matching calibrations carried by said slidably member on said support plate, said tabs being mounted on said support plate relative to said arcuate slots in laterally spaced distances corresponding to settings indicating hole spacings in types of buttons to be stitched, and said securing means being operative to secure said members in selected positions in said slots in said extensions wherein a selected calibration on said calibrated plate registers with a complementary tab members on said support plate, whereby a selected type of button may be properly attached to the work.

5. The invention defined in claim 1 including means for incapacitating the longitudinal movement of said table during the formation of said winding loops and locking stitches and maintaining said table so positioned relative to said needle that said winding loops and locking stitches are substantially centered between the underside of a button and the top surface of said work.

6. In a button stitching machine having means for projecting a threaded needle back and forth through selected button holes and the work to which a button is to be attached, comprising in combination a support table for said work, means for moving said table in a longitudinal path of travel relative to said needle, means for moving said table in a lateral path of movement relative to said needle whereby to position selected holes of said button in the path of travel of said needle, operating mechanism for actuating said means for effecting the movement of said table in said longitudinal and lateral paths of travel, means for controlling said mechanism to limit the extent of said movements of said table in accordance with the number of holes and spacing between the holes of a button being stitched, means for incapacitating the longitudinal movement of said table during the

table in said longitudinal and lateral paths of travel, means for controlling said mechanism to limit the extent of said movements of said table in accordance with the number of holes and spacing between the holes of a button being stitched, said operating mechanism comprising a cam shaft, a first group of cams on said cam shaft for moving said table along said longitudinal path of travel, a second group of cams mounted on said cam shaft, driving means for rotating said cam shaft once during each cycle of operation in stitching a button to the work, and adjustable means for selectively utilizing one cam of said first group and one cam of said second group in conforming the stitching operations of said machine to stitch a selected button to said work.

15 7. The invention defined in claim 6 wherein said actuating means for moving said table in said longitudinal and said lateral paths of travel, comprise a cam lever coacting with each of said groups of cams, an adjustably mounted cam follower on each of said levers, and means for securing each of said followers in a selected position on said cam lever for coaction with a selected cam of its corresponding group.

25 8. The invention defined in claim 7 wherein said means for moving said table in said longitudinal path of travel includes a lever, having an extension provided with an arcuate slot, a slidably adjustable member in said slot, a connecting rod connecting said cam lever which coacts with said first group of cams to said slidably adjustable member, and means for securing said member in a predetermined adjusted position in said slot to limit the longitudinal movement of said table to a distance corresponding to the spacing between the holes of a button being attached to the work.

35 9. The invention defined in claim 6, wherein said operating mechanism comprises a cam shaft, a first group of two cams on said cam shaft for moving said table along said longitudinal path of travel relative to said needle, a second group of three cams mounted on said cam shaft, means for driving said cam shaft to cause said cams to actuate said table moving means, means for causing a selected one of said cams of said first group of cams to move said table longitudinally when a two-hole button is being stitched, and to cause the second cam of said first group of cams to move said table longitudinally when a four-hole button is being stitched, and means for causing a selected cam of said second group of cams to move said table laterally relative to said needle during the formation of winding and locking stitches about the loops of thread connecting a two-hole button to the work, said last named means being adjustable to cause a selected one of the other two cams of said three cams to move said table laterally relative to said needle during the operation of said machine in attaching a four-hole button to said work with a parallel or cross stitch pattern, and means for operating said needle bars to pass said needle back and forth through selected holes in said button, and in forming thread windings and locking stitches in the thread connecting said four-hole button to said work.

40 10. In a button stitching machine having means for projecting a threaded needle back and forth through selected button holes and the work to which a button is to be attached, comprising in combination a support table for said work, means for moving said table in a longitudinal path of travel relative to said needle, means for moving said table in a lateral path of movement relative to said needle whereby to position selected holes of said button in the path of travel of said needle, operating mechanism for actuating said means for effecting the movement of said table in said longitudinal and lateral paths of travel, means for controlling said mechanism to limit the extent of said movements of said table in accordance with the number of holes and spacing between the holes of a button being stitched, means for incapacitating the longitudinal movement of said table during the

formation of said winding loops and locking stitches and maintaining said table so positioned relative to said needle that said winding loops and locking stitches are substantially centered between the underside of a button and the top surface of said work, said incapacitating means comprising a cam on said cam shaft, a cam lever having a cam follower coacting with said cam, a connecting rod connected at one end to said cam lever, a bell crank lever having one arm connected to the other end of said connecting rod, and the other arm of said bell crank being arranged to prevent movement of said actuating lever which effects longitudinal movement of said table, and said cam being so designed to maintain said last named arm in position to prevent forward movement of said table beyond a centered position relative to the underside of a button and the top surface of said work while said machine is forming winding and locking stitches

about and in the loops of thread attaching a button to the work.

5 11. The invention defined in claim 10 wherein means are provided for controlling the operation of said incapacitating means in accordance with the thickness of the work to which a button is attached.
